CARTON TRANSFER MECHANISM

Thomas E. Piazze, Mount Vernon, Ohio, assignor
to Shellmar Products Corporation, Chicago, Ill.,
a corporation of Delaware

Application September 27, 1946, Serial No. 699,764

3 Claims. (Cl. 198—24)

1

This invention has to do with carton machines. More particularly, it pertains to carton handling machines wherein collapsed cartons having top and bottom closure flaps have been opened, placed on a mandrel and the bottom flaps folded and glued together to provide a bottom closure, the carton being removed from the mandrel to a compressing unit by means of a novel transfer mechanism and that is a principal object of the invention.

Generally, it is an object of the invention to provide a transfer mechanism having means to receive cartons from the mandrel and to deliver them to another position for further handling, and means to eject the cartons from the transfer mechanism into a further handling unit for continued operation.

More specifically, it is an object of the invention to provide a transfer mechanism which includes a pivotally mounted carton receiving chamber to receive the cartons from the mandrel and to deliver them to another position for further handling, and an ejecting member cooperatively associated with the movement of the transfer mechanism to eject the cartons therefrom to another receiving means for further operation, such as the setting of the glued bottom closure.

Other objects of the invention will in part be obvious and will in part appear hereinafter.

The invention accordingly comprises the features of construction, combination of elements, and arrangement of parts, which will be exemplified in the construction hereinafter set forth and the scope of the application of which will be indicated in the claims.

For a fuller understanding of the nature and objects of the invention reference should be had to the following detailed description taken in connection with the accompanying drawings, in which:

Fig. 1 is a plan view, partly in section and with parts removed, of a transfer mechanism embodying the invention illustrated in cooperative association with a portion of a preferred type of carton machine;

Fig. 2 is a somewhat enlarged end elevational view, partly in section and with parts removed, of the transfer mechanism depicted in Fig. 1;

Fig. 3 is an end elevational view, partly in section and with parts removed, showing a portion of a presser mechanism used in conjunction with the carton machine for pressing the bottoms of the glued together flaps prior to their being ejected from the mandrel into the transfer mechanism.

Referring more particularly to the drawings, there is shown generally at 10 a preferred type of carton handling machine of the turret type carrying a plurality of mandrels 11. Each of

2

these mandrels shows a carton 12 having top and bottom closure flaps which previously has been opened from collapsed position, the bottom closure flaps having been glued and folded together, and being held and pressed in this position by the presser band 13 operated by the pressing mechanism indicated generally at 14. This latter mechanism is operated from a drive shaft 15 which receives its power through a gear 16 meshed with a gear 17 carrying a bevel gear 18 meshed with a bevel gear 19 on the main drive shaft 20 of the turret mechanism.

The pressing mechanism 14 is cam actuated by a cam 21 on the main drive shaft 15 through the linkage arrangement clearly illustrated in the mechanism generally indicated at 14. The cam 21 has a cam follower, or roller, 22 which actuates the arm 23 secured to the shaft 24. This in turn actuates the arm 25 against pressure of a spring 26 on a shaft 27 so that the shoes 28, 28, at the end of the linkage arrangement urge the resilient presser band 13 against the glued bottom flaps of the carton as an aid toward setting the closure as the mandrels 11 rotate the cartons 12 into this position. Thus, each carton is twice pressed as it is additionally wiped along the presser band 13.

Ultimately each carton is ejected from its mandrel by an ejector member 30 which constitutes a rod with a plate secured to the end reciprocably mounted within the mandrel. The carton is thus removed from the mandrel by having the plate at the end of the rod 30 pushing against the now glued together bottom closure in which the glue has not yet finally set.

A particular feature of the invention resides in the transfer mechanism for receiving each carton as it is ejected from the mandrel and delivering it to another position for further handling and thereafter bringing into operation another ejecting means to eject the carton from the transfer mechanism for further operations in connection with the carton.

The transfer mechanism preferably constitutes a receiving chamber indicated generally at 35 which consists of a base plate 36, a top plate 37 and a retaining pin 38 to hold the carton in position. This receiving chamber is secured to one arm of a bell crank type of lever 39 pivotally mounted on a stud 40. The other end of the bell crank arm is connected, by means of an adjustable link 41, to a cam arm 42 carrying a cam roller, or follower, 43 riding in a cam slot 44 of an actuating cam 45. This mechanism pivotally swings the transfer mechanism from the solid line position indicated, to the dotted line position for receiving the carton and then back again to the solid line position, whereupon the carton is ejected from the receiving chamber for further handling.

The ejecting mechanism comprises an ejection member, or pusher plate, 50 which in fact forms one wall of the chamber 35. This plate is connected to a slidably mounted or reciprocable bar 51 operating between gibs 52, 52. The reciprocable bar carries a stud 53 to which is connected an actuating arm 54 pivotally mounted at 55 on a stud upwardly projecting from the base plate directly below. The arm 54 is connected to another adjustable link 56 which in turn is connected to a cam arm 57 carrying a cam roller 58 riding in the groove 59 of the cam 60. The latter cam and the cam 45 for actuating the pivotally mounted receiving chamber are both mounted on the shaft 15 which also actuates the presser mechanism 14. As the carton 12 is received at its point of ejection from the mandrel 11, as shown in the dotted line position, it is returned to the solid line position and ejected from the receiving chamber by the wall plate 50.

The cartons which are now closed at their bottoms but with the top closure extension flaps still open are next received between the belts 61, 61, of a conveyor member. The belts aid further in pressing the glued bottom closure of the carton in position, holding them for a time sufficient to allow the glue between the bottom closure flaps to set thoroughly, and are adapted to convey the cartons with the opened flaps to a filling station after which the cartons can be closed 30 for shipping the packaged commodities.

Since certain changes may be made in the above construction and different embodiments of the invention could be made without departing from the scope thereof, it is intended that all 35 matter contained in the above description or shown in the accompanying drawings shall be interpreted as illustrative and not in a limiting sense.

It is also to be understood that the following 40 claims are intended to cover all of the generic and specific features of the invention herein described, and all statements of the scope of the invention which, as a matter of language, might be said to fall therebetween.

Having described my invention what I claim as new and desire to secure by Letters Patent is:

1. In a machine for handling cartons wherein formed cartons are carried on a series of mandrels on a turret and stripped from the mandrels in a direction radially of the turret for transfer to a conveyor arranged in a line generally tangential to the periphery of the turret, a transfer mechanism comprising a pocket forming member for receiving the cartons from successive 50 mandrels, a pivotally mounted bell crank, said pocket forming member being mounted on one arm of said bell crank, a cam-operated link pivotally connected to the other arm of the bell crank for oscillating the same between a carton 55 receiving position where the pocket forming member is in axial alignment with a mandrel on

said turret to a position where the pocket forming member is in transverse alignment with the conveyor, said pocket forming member having a wall movable transversely thereof and cam-operated means on said bell crank for moving said wall to deliver the carton from said pocket forming member to said conveyor.

2. In a machine for handling cartons wherein cartons are formed on a series of mandrels on a rotatable turret and successively stripped from the mandrels in a direction radially of the turret for transfer to a conveyor arranged in a line at an angle to the direction of movement of the cartons as they are stripped from the turret mandrels, a transfer mechanism between the turret and the conveyor comprising a pocket forming frame member for receiving the individual cartons from successive mandrels, said frame member being mounted for arcuate movement, a cam-operated link pivotally connected to the frame member for oscillating the same between a carton receiving position where the frame member is in alignment with a mandrel on said turret to a position where the frame member is in alignment with the conveyor, said frame member having a movable ejector plate and cam-operated means for moving said ejector plate to deliver the carton from said frame member to said conveyor.

3. In a machine for handling cartons wherein the cartons are carried on a series of forming mandrels on a turret and stripped from the mandrels in an axial direction for transfer to a conveyor arranged in a line at an angle to the movement of the successive cartons as they are stripped from the mandrels, a transfer mechanism between the turret and the conveyor comprising a pocket forming member for receiving the cartons successively from the mandrels, a pivotally mounted bell crank, said pocket forming member being mounted on one arm of said bell crank, a cam-operated link pivotally connected to the other arm of the bell crank for oscillating the same to position the pocket forming member successively in axial alignment with a mandrel on the turret and in end alignment with the conveyor, said pocket forming member having a movable back wall portion and cam-operated reciprocating means mounted on said bell crank for moving said wall portion to eject the cartons from said pocket forming member when it is aligned with said conveyor.
